PUFFED TEXTILE FABRIC

John C. Shell, Jr., Winnsboro, S. C., and Jack L. Larsen,
New York, N. Y., assignors to United States Rubber
Company, New York, N. Y., a corporation of New
Jersey

Application February 15, 1957, Serial No. 44,880

Term of patent 14 years

(Cl. D92—1)

Fig. 1 is a plan view of a puffed textile fabric, showing our new design;

Fig. 2 is a sectional view of the fabric of Fig. 1 along the line 2—2, and

Fig. 3 is a sectional view of the fabric of Fig. 1 along the line 3—3.

The design is embodied in a puffed textile fabric having a surface of raised puffs arranged as shown in Fig. 1. In the embodiment shown, the puffs are held raised by threads interlaced in the fabric such as that represented by the straight line in Fig. 2.

We claim:

The ornamental design for a puffed textile fabric, as shown and described.
